CLAIM

(73) Assignee: **SHENZHEN MAITEWEI INVESTMENT AND DEVELOPMENT CO., LTD.,**
Shenzhen (CN)

The ornamental design for wireless earbuds with charging case, as shown and described.

(**) Term: **15 Years**

DESCRIPTION

(21) Appl. No.: **29/727,238**

FIG. 1 is a perspective view of the wireless earbuds with charging case, shown with the wireless earbuds removed to show aspects of the design that are not visible when combined;

(22) Filed: **Mar. 9, 2020**

FIG. 2 is another perspective view thereof;

(51) LOC (12) Cl. **13-02**

FIG. 3 is a front elevational view thereof;

(52) U.S. Cl.

FIG. 4 is a rear elevational view thereof;

USPC **D13/108; D14/223**

FIG. 5 is a left side elevational view thereof;

(58) **Field of Classification Search**

FIG. 6 is a right side elevational view thereof;

USPC D13/107-108, 110, 118, 184, 199;

FIG. 7 is a top plan view thereof;

D14/432, 434, 205, 206, 223, 225;

FIG. 8 is a bottom plan view thereof;

D3/201, 205, 208, 218, 273, 274, 294,

FIG. 9 is a perspective view of the wireless earbuds with charging case, shown with the charging case removed to show aspects of the design that are not visible when combined;

D3/295; D24/174

FIG. 10 is another perspective view thereof;

CPC .. H02J 7/005; H02J 7/025; H02J 50/00; H02J

FIG. 11 is a front elevational view thereof;

50/10; H02J 50/12; H02J 50/40; H02J

FIG. 12 is a rear elevational view thereof;

50/402; H02J 50/50; H02J 50/80; H04R

FIG. 13 is a left side elevational view thereof;

1/10; H04R 1/1066; H04R 1/1016; H04R

FIG. 14 is a right side elevational view thereof;

25/00; H04R 5/033; H04R 5/0335

FIG. 15 is a top plan view thereof;

See application file for complete search history.

FIG. 16 is a bottom plan view thereof;

(56)
